Hector Zoia
BY *John A. Bonnahatt*

ATTORNEY

UNITED STATES PATENT OFFICE.

HECTOR ZOIA, OF WARRENSVILLE, OHIO.

SERVICE-HOLDER FOR CARRYING DISHES.

1,369,999.

Specification of Letters Patent.

Patented Mar. 1, 1921.

Application filed September 27, 1920. Serial No. 413,058.

To all whom it may concern:

Be it known that I, HECTOR ZOIA, a subject of the Government of Italy, residing at Warrensville, in the county of Cuyahoga and State of Ohio, have invented certain new and useful Improvements in Service-Holders for Carrying Dishes, of which the following is a specification.

This invention relates to devices used for carrying dishes containing food, and particularly adapted for use in hotels and other places where a number of dishes containing orders have to be carried at the same time. The present device is an improvement on the device for the same purpose shown in my U. S. Patent #1330568 dated February 10, 1920.

The object of the present invention is to provide an improved and simplified structure which may be applied to one dish in such manner that it cannot easily become dislodged therefrom, and which will support another dish at the top. A further advantage of the present device is that a number thereof can be nested together so as to occupy little space.

The invention is illustrated in the accompanying drawings in which Figure 1 is a vertical section of the device applied to a plate. Fig. 2 is a top view thereof. Fig. 3 is a sectional view showing how the devices are nested.

In the patent above referred to the shell consisted of two sections hinged together. In the present device, however, the shell is preferably made in one piece, consisting of an annulus indicated at 6, of sufficient width so that it will be high enough to hold an upper plate above the lower plate. This may be stamped or pressed from sheet metal, and the wall of the shell is inclined or tapered to a frusto-conical outline, so that one of the devices may be fitted within the other, as shown in Fig. 3.

The shell is provided at its lower edge with an outwardly curved lip or flange 7

which when the device is in use will engage over the edge of a plate 5, as shown in Fig. 1. This prevents the device from slipping off, and is somewhat more certain than 50 the rubber device provided for that purpose in my former patent.

At the top the edge of the shell is bent inwardly and curved to form a channel extending around within the rim, and in said channel is placed a rubber ring 8 the top of which projects above the upper edge of the shell. The upper plate may be seated on this ring and the base of the plate will fit within the ring and will thereby be held against accidental displacement. And so several more dishes may be piled one upon the other, and in which case the contents of the dishes will not be contacted by the successive plates, as the latter will be spaced apart by the shells, 65 in the manner disclosed in my former patent. The nesting feature shown in Fig. 3 is very convenient for storing the devices, and they can easily be picked up when needed. The cheapness and simplicity of structure are 70 obvious and it has numerous practical advantages, as will be apparent to waiters and others familiar with handling dishes.

I claim:

1. A dish holder comprising an annular 75 shell open at the top, the upper edge of the shell being provided with an inwardly curved channel, and a ring seated in said channel to engage the base of an upper plate.

2. A dish holder comprising a frusto-conical annular shell provided at its lower edge with a depending flange adapted to engage the rim of a lower plate, and providing its upper edge with a friction ring adapted to 85 support an upper plate.

In testimony whereof, I affix my signature in presence of two witnesses:

HECTOR ZOIA.

Witnesses:

G. W. ROSINBERG,
JOHN A. BOMMHARDT.
